CLAIM

The ornamental design for a camera mounting pedestal, as shown and described.

DESCRIPTION

FIG. 1 is a top, front, and first side perspective view of a camera mounting pedestal embodying the new design; FIG. 2 is a top, back, and second side perspective view thereof;

FIG. 3 is a front view thereof;

FIG. 4 is a back view thereof;

FIG. 5 is a first side view thereof;

FIG. 6 is a second side view thereof;

FIG. 7 is a top view thereof;

FIG. 8 is a bottom view thereof;

FIG. 9 is a top, front, and first side perspective view thereof with the camera mounting pedestal coupled to a camera; and,

FIG. 10 is a top, back, and second side perspective view thereof with the camera mounting pedestal coupled to a camera.

Any uniform repeating broken lines being presented depict portions of a camera mounting pedestal in which the claimed design is embodied and form no part of the claimed design.

1 Claim, 10 Drawing Sheets
